UNITED STATES PATENT OFFICE.

LEON F. PARKHURST, OF PITTSFIELD, MASSACHUSETTS. ASSIGNOR TO GENERAL ELECTRIC COMPANY, A CORPORATION OF NEW YORK.

ELECTRICALLY-HEATED TOOL.

1,026,363.

Specification of Letters Patent.

Patented May 14, 1912.

Application filed July 13, 1908. Serial No. 443,260.

To all whom it may concern:

Be it known that I, LEON F. PARKHURST, a citizen of the United States, residing at Pittsfield, county of Berkshire, State of 5 Massachusetts, have invented certain new and useful Improvements in Electrically-Heated Tools, of which the following is a specification.

This invention relates to electric heating 10 devices, and has for its object the provision of a device of this character in which the energy of an electric circuit is converted into heat in a thoroughly efficient manner, and which at the same time is exceedingly 15 simple to construct and is provided with easily renewable parts.

My invention relates more specifically to electrically-heated tools, such as shoe ironing tools and the like.

20 One of the objects of my invention is to provide a tool of this character in which the electric heating unit is of the self-contained character so as to be easily renewable, and is at the same time in intimate 25 thermal relation with the working surface of the tool. I accomplish this result by enclosing a heating unit of the self-contained cartridge type within a metallic tube and casting a mass of metal around the tube. 30 In this way an extremely simple device is obtained which is very efficient and in which the heating unit may be easily inspected and renewed.

In the accompanying drawing in which I 35 have shown my invention embodied in concrete form, Figure 1 is a side elevation of the device partially broken away to show the interior construction; Fig. 2 is an end view of the same; Fig. 3 is a section on the 40 line 3—3 of Fig. 1 with the unit removed; and Fig. 4 is a view of the complete device.

Referring to the drawing, 10 represents a metal tube, preferably of iron or steel, having handles 11 rigidly secured at its 45 opposite ends. Around this tube and intermediate the handles I have cast a body of metal 12, which may be iron or any other metal having suitable thermal qualities, and which will make a satisfactory joint with the tube. I have found that iron cast upon a steel tube suits the purpose very well. The body 12 is of a shape commonly used in 50 shoe ironing tools although it is evident that it may be formed into other tools without

departing from the spirit of my invention. 55 This metallic body 12 is elongated and has two working faces 13 and 14 which are rounded as shown. This body is cast on to the tube so as to be absolutely rigid, and ordinarily no fastening will be required between the body and the tube. An electric heating unit 15 is arranged to fit snugly within the tube so that it may be easily removed at will. This unit may be of any suitable type but for purposes of illustration I have shown the self-contained cartridge type which has been found very satisfactory. This unit is described and claimed in a patent to Vogel, No. 839,343, and consists of an edgewise resistance conductor 16 wound on edge in cylindrical form having both ends of the conductor 17 passing out through one end. This conductor is suitably insulated and covered with a metallic sheath 18 so as to bring it into 75 intimate thermal relation with the tube 10. The conductors 17 are insulated from each other by insulating beads 19 and brought out through one of the handles so that electrical connection may be made therewith 80 through pins 20 in the usual way. By this arrangement the heat from the unit is quickly and efficiently carried to the working surfaces 13 and 14 of the iron and the unit may be easily inspected and renewed 85 when necessary.

While I have described my invention in connection with a certain type of heating device constructed in a definite way, it should be understood that I do not limit 90 my invention thereto except in so far as it is limited by the scope of the claims annexed hereto.

What I claim as new and desire to secure by Letters Patent of the United States, is. 95

1. An electrically heated tool comprising a metallic tube, a mass of metal cast around the tube intermediate its ends, and a cylindrical heating unit slidably fitting into said tube so as to be in intimate thermal relation 100 therewith.

2. An electrically heated tool comprising a metallic tube having handles at opposite ends, a self-contained heating unit, slidably fitting into said tube so as to be in intimate 105 thermal relation therewith, and a mass of iron cast around the tube between the handles.

3. An electrically-heated tool comprising an elongated steel tube having handles at opposite ends, a mass of iron cast around the same intermediate said handles, and a self-contained heating unit within said tube and in intimate thermal relation therewith, said unit having conductors passing through one of said handles.

In witness whereof, I have hereunto set my hand this 10th day of July, 1908.

LEON F. PARKHURST.
